[57] CLAIM

The ornamental design for a recessed adjustable light fixture, as shown and described.

DESCRIPTION

FIG. 1 is a view as seen from the front and lower left of a recessed adjustable light fixture in a first position;

FIG. 2 is a view as seen from the rear and lower right of the light fixture of FIG. 1;

FIG. 3 is a bottom plan view of the light fixture of FIG. 1; FIG. 4 is a front elevational view of the light fixture of FIG. 1;

FIG. 5 is a rear elevational view of the light fixture of FIG. 1;

FIG. 6 is a right side elevational view of the light fixture of FIG. 1;

FIG. 7 is a left side elevational view of the light fixture of FIG. 1;

FIG. 8 is a view as seen from the front and lower left of another embodiment of a recessed, adjustable light fixture in the position shown in FIG. 1;

FIG. 9 is a front elevational view of the light fixture of FIG. 8;

FIG. 10 is a view as seen from the front and lower left of the light fixture of FIG. 1 in a second position; and,

FIG. 11 is a bottom plan view of the light fixture of FIG. 10. The light fixture of FIG. 8 is identical to the light fixture of FIG. 1 except in the respects shown in FIGS. 8 and 9. The broken lines are shown for illustrative purposes only and form no part of the claimed design.

The second embodiment shown in FIGS. 8 and 9 is identical to the first embodiment except for the additional front grill. The broken lines are shown for illustrative purposes only and form no part of the claimed design.
